FLAG HOLDER

James W. Lane, Pawhuska, Okla.

Application March 29, 1935, Serial No. 13,780

1 Claim. (Cl. 116—173)

This invention appertains to new and useful improvements in flag staffs, and more particularly to a staff having a portion thereof hollow for concealing and protecting the flag when its use is not desired.

The principal object of the present invention is to provide a flag holder which can be utilized for displaying the flag which can be rolled up inside of the holder to protect it against weather conditions.

During the course of the following specification other important objects and advantages of the invention will become apparent to the reader.

In the drawings:

Figure 1 is a side elevational view of the container portion of the holder.

Figure 2 is a longitudinal sectional view through the holder.

Figure 3 is a side elevational view of the internal tube.

Figure 4 is a side elevational view of the external tube.

Figure 5 is a sectional view taken substantially on line 5—5 of Figure 1.

Figure 6 is a cross sectional view taken substantially on line 6—6 of Figure 1.

Referring to the drawings wherein like numerals designate like parts, it can be seen that numeral 5 represents a cylindrical structure having an enlarged circumferentially extending intermediate portion 6. Numeral 7 represents the peak or top knob of the staff having a shank portion 8. A connecting tube 9 receives the shank 8 and engages over the upper portion of the cylindrical block 5. The lower portion of the cylindrical block 5 engages into the internal tube 10 at its upper end and suitable securing means 11 is provided at this point for definitely and positively securing the inner tube 10 to the section 5. A block 12 is provided in the lower portion of this tube 10 for receiving the shaft like extension 13 of the roller 14 which, at its upper end, is provided with a spring ratchet detent (similar to those found on shade rollers) which has the pin 16 thereof engaged into the lower end of the section 5; the block 12 is keyed to the tube 10 as at 12a. Suitable retaining members

17 are provided on the roller 14 for holding the inner end of the flag 18.

The tube 10 is provided with an elongated longitudinally extending slot 19 which is registerable with the elongated slot 20 in the external tube 21 which tube 21 circumscribes the tube 10 and abuts the shoulder 22 on the tube 10 at its lower end. The tube 10 engages into one end of the sleeve 10a, the sleeve abutting the shoulder 22 at one end, as shown in Figure 2, while the other end of the sleeve is engaged over the upper end of the staff.

It will be observed that the edge portions of the tubes 10—21 and the slots 19—20 are cut away at points indicated by the numeral 24 to permit the finger of a person's hand to be inserted to grasp the flag so that it can be unwound. Obviously, when the flag is retracted into the tube 10, the other tube can be rotated so as to close off the slot 19 and thus entirely engage and protect the flag.

While the foregoing specification sets forth the invention in specific terms, it is to be understood that numerous changes in the shape, size and materials may be resorted to without departing from the spirit and scope of the invention as claimed hereinafter.

Having described the invention what is claimed as new is:—

A flag holder comprising an inner tube, an outer tube concentric to and rotatable with respect to said inner tube, said tubes being provided with registering slots therein, a block in the lower portion of the inner tube, a body at the upper edges of the tube having a portion 35 extending into the upper end of the inner tube, a roller having its ends engaged with the said body and the block and having a flag mounted thereon for movement through said slots when in registry, a circumferentially extending shoulder on the outside of the inner tube with which the lower edge of the outer tube abuts, the lower end portion of the inner tube depending below the lower end of the outer tube, a tubular section into which the lower end of the inner tube 40 extends and a flag staff extending at its upper end into the said tubular section.

JAMES W. LANE.
